COVER FOR LAVATORY SPOUT

Ralph La Rue Du Bois, 4242 E. 111th St.,
Tulsa, Okla. 74135

Continuation-in-part of abandoned design application Ser. No. 23,112, May 25, 1970. This application July 12, 1971, Ser. No. 161,379

Term of patent 14 years

Int. Cl. D23—01
U.S. Cl. D23—32

FIG. 1.

FIG. 2.

FIG. 3.

FIG. 4.

FIG. 5

FIG. 1 is an elevational view taken from one side of a cover for lavatory spout showing my new design, the opposite side being a mirror image of the side shown;

FIG. 2 is a top plan view thereof;

FIG. 3 is a bottom plan view thereof;

FIG. 4 is a rear elevational view thereof; and

FIG. 5 is a front elevational view thereof.

I claim:

The ornamental design for a cover for lavatory spout, substantially as shown and described.
